UNITED STATES PATENT OFFICE.

CHARLES W. JEAN, OF NEW YORK, N. Y.

METHOD OF PRODUCING PRESS-COPIES.

1,281,781.

Specification of Letters Patent. Patented Oct. 15, 1918.

Application filed January 22, 1917. Serial No. 143,800.

To all whom it may concern:

Be it known that I, CHARLES W. JEAN, a citizen of the United States, residing at New York, in the county of New York and State of New York, have invented certain new and useful Improvements in Methods of Producing Press-Copies; and I do hereby declare the following to be a full, clear, and exact description of the invention, such as will enable others skilled in the art to which it appertains to make and use the same.

This invention relates to the method of making off-set copies, ordinarily known as press copies, of letters or like documents whereas each letter is copied upon a continually moving sheet or web of tissue or like copying paper, which web of paper is held in constantly taut condition from the time it leaves the roll until it is delivered to the shear in dry and smooth condition carrying the impregnated or off-set copies thereon, said shear being provided for severing the web into such sections as may be necessary to properly separate the copies.

While in the practice of the present process mechanical means are ordinarily employed for carrying forward the several steps of the process, the particular mechanical means are immaterial to the present invention, one being shown in application Serial No. 29414, filed May 20, 1915, and the mechanical disclosure thereof reproduced herein as a means for carrying into effect the present method.

In the drawing, taken without change from said application No. 29414:

Figure 1 is a sectional view showing the path of movement of the web of copy paper, and the means for maintaining it in taut position.

Fig. 2 is a view of such mechanical structure in side elevation showing the means for moving the several parts.

Fig. 3 is a fragmentary detail view of the tension mechanism.

Like characters of reference designate corresponding parts throughout the several views.

In employing the mechanical structure shown in the drawings, for carrying into effect the present method, a roll of tissue or copy paper is maintained at 10 carried upon the general frame 11 of the structure. The roll 10 is mounted upon a beam 12 having a

tension device 13 resisting rotation of the beam 12 and web 10.

From the beam 12, the paper strip 10 passes between moistening rolls 14 and 15, one of which, as the roller 14, moves in the trough so that the web 10 passing between such rollers is subjected to a moistening effect.

To properly position the web for receiving the documents and also for the purpose of extracting excess moisture therefrom, the web is carried over a roller 16, and between such roller 16 and the compression roller 17.

Conveniently located above the sheet 10 after passing over the roller 16 is a table 18 upon which the letters or other documents to be copied are placed, and from which they are fed upon the sheet 10 as it passes between the rollers 19 and 20, which rollers not only serve the purpose of assisting the advancing of the traveling sheet 10, but also exert compression upon the documents placed on said sheet so that the sheet being moistened, the printing, writing or other matter to be copied appearing upon such sheets is off-set upon such moistened sheet which sheet it impregnates in the usual well-known manner with such copied matter.

After passing between the rollers 19 and 20 the said sheet 10 passes over a heated roller 21 maintained in heated condition in any approved manner, as, for instance, by the employment of the fluid fuel burner 22 shown at Fig. 1 supplied with a fluid fuel through and by any convenient conduit as shown at 23 in Fig. 2. An idle roller 24 is employed to properly smooth out and position the sheet 10 upon the heated roller 21, and the document copied after passing between such rollers 21 and 24 is discharged from the copied sheet in any approved manner as by being manually removed or falling out by gravity. A second idle roller 25 is employed so that the sheet 10 received upon the heated roller 21 in a moistened condition is carried about as large a portion of the circumferential travel of said roller as convenient so that the heat of said roller may dry said sheet before it is carried farther on its travel.

After passing over the idler 25 the sheet 10 is carried between feed rollers 26 and 27 conveniently close to which is located the

shear 28 operated in an approved manner for severing sections of the sheet carrying the offset and impregnated copy.

The peripheries of the several rollers 14, 16, 19, 21 and 26 are driven by approved transmission mechanism as shown at Fig. 2 or otherwise, so that all the said peripheries travel coincidentally, thereby maintaining the sheet in taut condition without subjecting said sheet to pulling stress caused by the periphery of one roller traveling faster than the periphery of another, endangering thereby the severance of the sheet at undesired points. The entire mechanism is driven in any approved manner, a motor 29 being shown, but it being understood that the application of motor force is immaterial to the present invention.

The machine shown, therefore, accomplishes the carrying forward of the present method in that the parts being rotated by any approved means as the motor shown, the sheet 10 travels from the beam 12 between the moistening rollers, between the extracting rollers, and then forms a plane surface from such extracting rollers to the heating surface located between which are the compression rollers 19 and 20. The document is applied to the sheet at this point, and being carried between the compression rollers 19 and 20 off-sets its matter in the usual well-known manner. The sheet being maintained in traveling constantly in a smooth condition about the heated roller is dried in such smooth condition and is delivered to the shear in such dry and smooth condition for severance into the necessary sections for filing or other use in the usual well-known manner.

40 What I claim is:—

1. The method of producing a dry off-set copy of a document consisting in employing a traveling sheet of copy paper maintained in taut condition, applying moisture to said sheet, positioning the document upon the sheet, subjecting the sheet and document to pressure, drying the sheet by contact with a heated surface traveling coincidentally with the sheet, and finally severing the section of the sheet impregnated with the off-set copy while yet maintaining said traveling and taut condition of the remaining sheet.

2. The method of producing a dry off-set copy of a document consisting in employing a traveling sheet of copy paper maintained in taut condition, applying moisture to said sheet, positioning the document upon the sheet, subjecting the sheet and document to pressure, drying the sheet by contact with a heated surface traveling coincidentally with

the sheet, and delivering the sheet dried by such contact to proper position for severing in sections.

3. The method of producing a dry off-set copy of a document consisting in employing a traveling sheet of moistened copy paper maintained in taut condition, positioning the document upon the sheet, subjecting the sheet and document to pressure, drying the sheet by contact with a heated surface traveling coincidentally with the sheet, and severing the dried sheet into sections carrying the impregnated copy.

4. The method of producing dry off-set copies of documents consisting in employing a traveling sheet of copy paper maintained in taut position, applying moisture to said sheet, positioning the document upon the sheet, subjecting the sheet and document to pressure, and drying the sheet in contact with a heated surface, and finally severing the sections of the sheet impregnated with the off-set copies while yet maintaining said traveling and taut condition of the remaining sheet.

5. The method of producing dry off-set copies of documents consisting in employing a traveling sheet of copy paper, applying moisture to said sheet, placing the documents on the sheet, subjecting the sheet and documents to pressure, drying the sheet by contact with a heated surface traveling coincidentally with the sheet, and finally severing the sections of the sheet impregnated with the off-set copies.

6. The method of producing a dry off-set copy of a document consisting in employing a traveling sheet of copy paper maintained in taut condition, applying moisture to the traveling sheet, applying the document to be copied to the sheet, subjecting the document to pressure to bring it into intimate engagement with the sheet, removing the document from the sheet, drying the sheet by contact with a traveling heated surface, releasing the end of the sheet from taut condition, and severing the released end.

7. The method of producing dry off-set copies of a document consisting in employing a traveling sheet of semi-transparent paper, maintaining the traveling sheet in taut condition, applying moisture to the sheet, impressing the document to be copied upon the moistened sheet, removing the document from the sheet, drying the sheet by contact with a heated surface, releasing the forward end of the traveling sheet from taut condition, and severing the released portion.

In testimony whereof I affix my signature.
CHARLES W. JEAN.
